J. ANTLE.
ERASER HOLDER FOR PENCILS.
APPLICATION FILED FEB. 15, 1916.

1,248,988.

Patented Dec. 4, 1917.

UNITED STATES PATENT OFFICE.

JOHN ANTLE, OF HARRISON, IDAHO.

ERASER-HOLDER FOR PENCILS.

1,248,988.

Specification of Letters Patent.

Patented Dec. 4, 1917.

Application filed February 15, 1916. Serial No. 78,478.

To all whom it may concern:

Be it known that I, JOHN ANTLE, a subject of the Emperor of Germany, residing at Harrison, in the county of Kootenai and 5 State of Idaho, have invented certain new and useful Improvements in Eraser-Holders for Pencils, of which the following is a specification.

My invention relates to new and useful 10 improvements in eraser holders, the primary object of my invention being the provision of a novel form of holder for detachably connecting an eraser to the end of a pencil, the construction being such that the 15 pencil may at any time be removed and a new one substituted in its place and further such that as the eraser becomes worn it may be adjusted so as to project beyond the holder until substantially worn out when 20 the remainder may be removed and a new eraser substituted.

A still further object of my invention consists in providing a device of the above described character in which the eraser when 25 in place will be held against any movement with respect to the pencil.

A still further object of my invention consists in providing an eraser holder capable of holding an eraser of much greater 30 size than that commonly employed in connection with pencils and so shaped that in use it will prevent rolling of a pencil when placed upon an inclined surface.

With these and other objects in view, my 35 invention will be more fully described, illustrated in the accompanying drawings, and then specifically pointed out in the claim which is attached to and forms a part of this application.

40 In the drawings:

Figure 1 is a perspective view of my improved device in use;

Fig. 2 is a fragmentary front elevational view, a portion being shown in section to 45 illustrate certain details in construction;

Fig. 3 is a side elevation of the structure shown in Fig. 2;

Fig. 4 is a transverse sectional view taken on the line 4-4 of Fig. 2, looking in the 50 direction of the arrows.

Corresponding and like parts are referred to in the following description and indicated in all the views of the drawings by the same reference characters.

55 Broadly speaking, my invention, the body of which is preferably formed in one piece,

includes a sleeve portion 10 adapted to receive the unpointed terminal of a conventional pencil 11 and the head portion 12 adapted to receive and grip an eraser 13. 60 More specifically, this body, which is preferably formed of resilient sheet metal, has the cylindrical sleeve 10 provided adjacent the head 12 with the instruck stop bead 14 which serves as an abutment to engage the 65 end of a pencil inserted in the sleeve to limit its movement and thus prevent its forcing the eraser out of engagement with the head. This sleeve, adjacent the bead, is provided with an opening 15 and a slot 16 extends 70 longitudinally from this opening through the free end of the sleeve in order that the sleeve, which is resilient, may spread somewhat to receive a pencil and firmly grip the pencil when the latter is in place. Because 75 of this arrangement, the device may be applied to pencils of slightly differing diameters or to pencils which are circular or angular in cross section. The head portion 12 includes the base 17 and the co-acting 80 clamping jaws 18 and 19. This head, as a whole, is substantially rectangular in cross section, being approximately equal in thickness to the diameter of the pencil receiving sleeve but of considerably greater width in 85 order that a pencil provided with my attachment laid upon an inclined surface may be prevented from rolling and in order to adapt it to receive a relatively large eraser. This head is in effect formed of a rectangular 90 tube provided in its wider faces with T-shaped slots 20, the heads of which are located near the base 17 and the stems of which open through the free end of the head. By this means, the co-acting jaws 18 95 and 19 are formed, each jaw being substantially U-shaped in cross section with its edges spaced from the adjacent edges of the other jaw and the jaws being free for movement toward and away from each other because 100 of the slot and the resiliency of the material of which they are formed. These jaws, adjacent their free ends, are provided with outwardly directed beads or shoulders 21 which form stops, as will be later described 105 and in spaced relation to these beads or shoulders with out struck lugs or shoulders 22 having those faces more remote from the beads 21 beveled or inclined, as best shown in Fig. 2. The edges of the bight portions 110 of the jaws 18 and 19 are instruck to provide opposed teeth 23 to engage in an eraser

inserted in the head and the jaws are forced into engagement with the eraser by a locking ring 24. This ring corresponds in cross sectional shape to the shape of the head and is proportioned to slide along the head until stopped by engagement with the beads or shoulders 21 at which time it also engages the shoulders 22 and is therefore held against accidental movement in either direction. Preferably, the outer face of this ring is corrugated or otherwise roughened, as shown, to facilitate its manipulation.

The eraser 13, as shown, is of the same cross sectional shape as the clamping head 12 and has one end squared to engage against the base of the head when in place. Preferably, the outer end of the eraser is beveled or wedge-shaped, as clearly shown in the drawings.

After forming the body of my improved eraser holder, the ring 24 may be applied to it by passing it over the pencil receiving sleeve 10 and onto the lower end of the head 12. An eraser 13 may then be positioned in the head and the sleeve forced outwardly until locked between the shoulders 21 and 22 to lock the eraser in place. The holder, together with the eraser, may then be applied to any desired pencil. Obviously, if it is to be employed in connection with an indelible pencil, an ink eraser may be employed instead of the ordinary pencil eraser

or the holder with an ink eraser in it may be applied to the end of a pen, if desired. As the eraser becomes worn, the ring may be slipped back and the eraser partially withdrawn from time to time and again clamped in place by replacing the ring. By this means, it is possible to wear out nearly all of the eraser before it need be replaced by another. With the jaws of the shape shown and with the clamping ring clamped about the jaws near their free ends, a firm grip is maintained upon the eraser such as will hold it from movement in any direction.

Having thus described the invention, what is claimed as new is:

An attachment for pencils including a body formed at one end to provide a cylindrical pencil receiving sleeve and at its other end to provide an eraser holding head, the head portion being substantially rectangular in section and substantially equal in thickness to the diameter of the sleeve and of considerably greater width whereby when a pencil is mounted in the sleeve and laid upon a support it will be held against rolling movement, the walls of the head being abruptly merged into those of the sleeve to provide an enlarged seat for the inner end of an eraser mounted in the head, and means for locking an eraser in the head.

In testimony whereof I affix my signature.

JOHN ANTLE. [L. S.]
